UNITED STATES PATENT OFFICE

THOMAS B. STILLMAN, OF SOUTH ORANGE, NEW JERSEY, ASSIGNOR TO THE BABCOCK & WILCOX COMPANY, OF BAYONNE, NEW JERSEY, A CORPORATION OF NEW JERSEY

BOILER UPTAKE

Application filed April 3, 1928. Serial No. 266,934.

This invention relates to an installation of marine boilers that operate in boiler rooms that are maintained at super-atmospheric pressure to produce forced draft, and will 5 be understood from the description in connection with the accompanying drawings, in which Fig. 1 is an end view in section and somewhat diagrammatic, showing an illustrative embodiment of the invention, and Fig. 2 10 is a section along the line 2—2 of Fig. 1.

In the drawings, reference character 1 indicates the hull of a ship and the sea level is indicated at 2. The ship is provided with an air-tight boiler room 3 that is maintained at 15 super-atmospheric pressure by means of the air pressure fan 4, so that forced draft is thereby maintained through the boiler furnaces.

It has been found that in some present installations of this character in which closed forced draft fire-rooms are used, gas sometimes escapes from the uptake or smoke-stack leading away from the boilers or fire-room into the living quarters of the ship. This 20 seeping or leaking of the gas is caused by the fact that the gas leaving the boilers through the uptakes and stacks is somewhat above atmospheric pressure and, therefore, leakage takes place unless the uptakes and stacks are 25 absolutely tight. It is expensive to make the uptakes absolutely tight, and the present invention obviates the objection above referred to in a very simple and inexpensive manner. The invention is illustrated with a ship with 30

two boilers located side by side in the fire-room, but the invention is also applicable to any other number of boilers. The boilers as illustrated each have an upper or steam and water drum 5 and lower drums 6 connected 35 by banks of tubes in the well-known manner in boilers of this type. The furnaces of the boilers are indicated at 7 and uptakes 8 for waste products of combustion lead from the upper portions of the boiler to a stack or flue 40 9 that leads to an outlet 10 on the side of the ship.

The stack or flue 9 is surrounded by an outer casing 11 that is air-tight and is spaced from the stack or flue so as to leave a space, as indicated at 12. The end of the casing 11 is

closed, as indicated at 13, and the space 12 between the casing 11 and the flue 9 communicates with the boiler room, as indicated at 14. The invention is applicable either to a vertical or horizontal or inclined flue or stack 45 or uptake.

The operation is as follows: The fan 4 forces air into the boiler room 3 and maintains a pressure therein above atmospheric. The air pressure in the boiler room causes the air to enter the furnaces 7 of the boilers under forced draft and the pressure through the uptakes 8 and flue 9 is consequently usually slightly above atmospheric pressure. This is especially true when the uptakes lead horizontally through the side of the ship, thus eliminating practically all tendency to secure a natural draft, and it is sometimes true even with ships that are equipped with relatively vertical uptakes and stacks to produce a fairly strong natural draft. The air pressure in the boiler room 3 causes air to pass through the openings 14 into the space 12 around the flue 9, thus preventing any gas from escaping through cracks or leaks that may be in 55 the flue. In view of the fact that the end of the space 12 is closed, as indicated at 13, this does not cause waste of air, except the small amount of air that may pass directly into the flue 9 from the space 12 to prevent leakage 60 of gas in the other direction. Either the flue 9 or the casing 11 may be insulated with heating insulating material, if desired.

I claim:

1. A ship having a boiler room in which super-atmospheric pressure is maintained, a smoke-stack extending from the boilers in said room to the outside, means comprising a casing spaced from said stack to prevent leakage of gases from said stack, and means 85 to maintain boiler room pressure in the space between said stack and casing.

2. A ship having a boiler room in which super-atmospheric pressure is maintained, a smoke-stack extending from the boilers in 90 said room to the outside, and a casing surrounding said stack preventing leakage from said stack, the inside of said casing being subjected to boiler room pressure.

3. A ship having a boiler room in which 100

super-atmosphere pressure is maintained, a smoke-stack extending from the boilers in said room to the outside, a casing surrounding said stack preventing leakage from said stack, said casing being spaced from said stack, and means to maintain super-atmospheric pressure in the space between the stack and casing.

4. A ship having a boiler room in which super-atmospheric pressure is maintained, a smoke-stack extending from the boilers in said room to the outside, a casing surrounding said stack preventing leakage from said stack, said casing being spaced from said stack, and means to maintain substantially the same pressure in the space between said stack and casing as in said boiler room.

5. A ship having a boiler room in which super-atmospheric pressure is maintained, a smoke-stack extending from the boilers in said room to the side of said ship, and a casing surrounding said stack preventing leakage from said stack, the inside of said casing being subjected to boiler room pressure.

6. A ship having a boiler room in which super-atmospheric pressure is maintained, a smoke-stack extending from the boilers in said room to the outside, and an air-tight casing surrounding said stack, the inside of said casing being subjected to boiler room pressure.

7. A ship having a boiler room in which super-atmospheric pressure is maintained, a smoke-stack extending from the boilers in the said room to the outside, a casing surrounding said stack where it passes through the quarters of the ship above the fire-room, said casing being spaced from said stack and means to maintain substantially the same pressure between the said stack and casing as in said boiler room to prevent leakage of gases from said stack into the quarters of the ship above the boiler room.

8. A ship having a boiler room in which super-atmospheric pressure is maintained, a smoke-stack extending from said boiler room to the outside, a casing surrounding said stack preventing leakage from said stack, said casing being spaced from said stack, and the space between the stack and casing being connected by means of openings to the boiler room so that the super-atmospheric pressure existing in the boiler room will be carried to every portion of the space between the stack and casing surrounding said stack.

THOMAS B. STILLMAN.
